UNITED STATES PATENT OFFICE.

GEORGE A. LORING AND GEORGE N. SEAMAN, OF BOSTON, MASSACHUSETTS.

DESIGN FOR A NAPKIN.

SPECIFICATION forming part of Design No. 24,848, dated November 5, 1895.

Application filed July 27, 1895. Serial No. 557,389. Term of patent 14 years.

To all whom it may concern:

Be it known that we, GEORGE A. LORING and GEORGE N. SEAMAN, citizens of the United States, residing at Boston, in the county of Suffolk and State of Massachusetts, have invented and produced a new and original Design for Napkins, of which the following is a specification, reference being had to the accompanying fac-simile drawing, forming part thereof.

The drawing herewith presented illustrates in plan a napkin embodying our design.

The essential features of our design comprise a number of Masonic symbols arranged in an artistic grouping to form a border for a napkin wholly or in part about the edge.

The particular features of our design are embodied in a rectangular space or border inclosed by straight lines drawn a suitable distance from the edge of the napkin. Within this space and constituting the ornamentation or figuring and which forms the border are grouped a number of Masonic symbols representing different degrees in Masonry.

In order that the best effect may be pro-

duced from the grouping, which is obtained by placing it before the observer in a particular way—that is, making a top and bottom to the napkin—the lower border-line is extended from the sides across the bottom of the napkin only in part, leaving an open space. Within said space on either side are placed two columns surmounted by spheres, while the columns extend beyond the border-line within the body-space of the napkin. Above and between said columns appears a symbol representing the eye of knowledge, and below, but between the bases of the columns, is the symbol representing the thirty-third degree.

What we claim is—

The design for a napkin, as herein shown and described.

In testimony whereof we affix our signatures in presence of two witnesses.

GEORGE A. LORING.
GEO. N. SEAMAN.
